UNITED STATES PATENT OFFICE

2,489,497

ELECTRICAL MUSICAL INSTRUMENT

James A. Oswald, Chicago, Ill., assignor to Central Commercial Company, Chicago, Ill., a corporation of Illinois

Application March 20, 1946, Serial No. 655,835

9 Claims. (Cl. 84—1.19)

1

This invention relates to electrical musical instruments and more particularly to keyboard instruments, the playing-keys of which are coactive with generators of tone signal voltages and with an electroacoustical translating device for conversion of signal voltages from selected generators into audible sound for musical expression. In the instant embodiment of my invention, reference is made to a single keyboard as illustrative of a simple but practical and musically useful application of my invention. Reference will be made to only a minimum number of tone frequency or waveform generators, such that for each playing-key of the instrument there will be one generator individual thereto, but connected in an electrical network for concurrent transmission through separate channels of divided portions of the output wave from said generator, whereby a note of the same pitch can be sounded in response to selective, concurrent actuation of respective instrumentalities of the instrument, such as stops, playing-keys of one or more keyboards, or the keys of a pedalboard. The herein disclosed embodiment of my invention will be sufficient to teach persons trained in the art in use of the underlying features of my invention for a great variety of purposes and accompanying increase in the musical possibilities of an instrument of this class.

The pitch of organ stops is spoken of, relative to the ordinary pitch, for example, of the violin. Taking the open G string of the violin, a note of the same pitch is called 8-foot tone. But, on the organ, a stop may be drawn giving the same tone and the same color one octave higher, called 4-foot tone. Similarly, each tone color, in general, may be produced from the same key at pitches varying from two octaves lower to two octaves higher. In exceptional cases, this may be expanded to provide 64-foot and 1-foot tones. On the organ this is accomplished by bringing into use various sets of pipes, the total number of which determines the pitch range of the instrument. In a single manual instrument having sixty-one playing-keys and an alternator or wave generator for each individual playing-key, octave coupling by means of stops is limited, due to the fact that the lowest frequency produced by any generator is approximately 65 cycles per second, the highest frequency being approximately 2093 cycles per second. Obviously, if the range is to be extended either up or down from one or the other of these pitches or both up and down therefrom additional generators will be required. It suffices to say that in most instances, the range will be extended, at least to include a 16-foot tone.

An object of my invention is the provision of a simple and dependable system of generators and stops, whereby octavely related generators can be selectively drawn upon for concurrent distribution of their output waves through an electrical network, and similarly, concurrently translated

2

into audible sound of two or more pitches of the same tone color. This is accomplished by depressing any selected playing-key of an assigned number of keys in the instrument's gamut and by the selective drawing of stops.

A further object is the provision in an electrical network, of means enabling concurrent distribution of divided portions of the waveforms of voltages from selected generators in a manner insuring that the divided portions of any selected wave are the same in amplitude.

A still further object is the provision of means in a keyed instrument employing alternators or generators of tone signal voltages for suppressing noise, such as "key thump" or "pop" heretofore unavoidably resulting in consequence of sudden electron surges when close circuiting said alternators or generators with the input circuit of an amplifier.

My invention, though it may find expression in various embodiments has, common to each thereof, the broad idea of the combination of resistances and wave generators which are so connected in an electrical network that proportionality in amplitude of divided portions of the output of any generator is effectively secured regardless of the number of said portions being transmitted at the same instant to a translating device, and whereby, when any generator is close circuited with said translating device, there will be such attenuation of said portions that extraneous frequencies heretofore resulting in objectionable noise will be extinguished.

My invention is illustrated in the accompanying drawings in which Figures 1 to 4, inclusive, are diagrams illustrating the broad form of my invention; Figures 5 to 13, are respective parts of a composite network embodying my invention; Figure 14 is a diagram employed as a reference key to the sequence of Figures 5 to 13 to form a composite of said figures; Figure 15 is a perspective view of one of the electric switches, and Figure 16 is a longitudinal section through said switch showing an application thereof to a playing-key.

A comprehensive understanding of the principle and modus operandi of the main characterizing features of my invention will be had upon referring to the schematic graphs and circuits shown at Figures 1 to 4, inclusive of the accompanying drawings. In Figure 1, curve *a* is typical of the gradual attack and decay of a pipe tone. Curve *b* is typical of the percussive attack of a struck string as that of the piano. Due to the fact that both the ear drum and the cone or diaphragm of a loud speaker have inertia and resilience, the attack of curve *c* is characteristic of sound, which, to the ear is represented by curve *d* and is responsible for an unpleasant "thump" or "pop" similar to that which typifies sound emitted from any percussive instrument.

At Figure 2 a simple voltage divider circuit is illustrated. In this figure voltage E is impressed between points 1 and 2 by battery B . By Ohm's law, the voltage V which will be measured between 3 and 4 will be

$$V = E \frac{R_1}{R_1 + R_2}$$

If R_2 is a fixed resistance and R_1 a resistance which is variable from zero to some finite value, V then becomes a function of R_1 . We will assume that R_1 is connected by some mechanical arrangement to a depressible operating key K in Figure 3 in such manner that gradual descending motion of the key gradually increases the resistance of R_1 from zero when the key is fully elevated and at rest to some finite value when the key is depressed. Thus, it becomes apparent that by proper selection of the taper of resistance R_1 or by proper mechanical linkage between the key and R_1 or by a combination of the two, that any growth of voltage can be attained for a linear movement of the key and that the exponential rise of curve a , Figure 1 may be attained, thereby suppressing the objectionable "thump" or "pop" that otherwise would be experienced.

If we substitute a source of audio signal for the battery of Figure 2 and the playing-key of an organ or other keyboard instrument for the key K of Figure 3, we can let the curves of Figure 2 represent signal voltage (RMS) or tone intensity delivered to the amplifiers. The simple circuit of Figure 3, however, has other restrictions placed on it for use in an instrument circuit. For example, while the larger R_1 becomes relative to R_2 more signal is delivered and the less the loss in the circuit, it is necessary, however, to restrict R_1 to a low value compared to R_2 in order that the generating source shall not be subject to too wide a variation in load between key up and key down conditions and also in the case where a given tone frequency is used on more than one key-(octave couplers or more than one manual), and to prevent "robbing" between these two or more keys. In addition, since it is necessary to combine the outputs of several keys to form a single channel, isolating resistors must be used to prevent the grounding of the common channel by any key in the group which is not depressed. In this same connection the isolating resistor must be high compared to R_1 and also to the impedance of the common channel if "robbing" is to be prevented.

Figure 4 shows a practical circuit using this method of keying when S is the audio frequency source, P_1 an output path connecting the plate circuit of source S to a common conductor X . Conductor X is connected to the input circuit of an amplifier A , the latter grounded at G . Connected in series in said path P_1 are fixed resistors R_2 and R_3 . Connected across said path at the juncture point between said resistors R_2 and R_3 is a variable, key operated resistor R_1 , the same grounded at G_2 . Resistor R_2 will be hereinafter referred to as an isolating resistor and R_3 a protective resistor. Resistor R_2 constitutes an element of a potential divider, and is connected in parallel with a plurality of similar fixed resistors R_2' in respective signal output paths P_2 . R_3' are paths to common conductor X from respective audio frequency sources which will be hereinafter shown and referred to in complete detail.

As R_1 is increased from zero to its maximum value by operation of its associated key the signal applied to the grid of the amplifier A will rise

smoothly by any curve selected to a maximum value. This maximum signal will be maintained until the key is released and at that time the signal will be smoothly reduced to zero as the key rises. As previously stated, the curve of the "attack" and "decay" can be made to have any form desired by proper selection of resistance taper and mechanical linkage.

In the accompanying drawings, Figures 5 to 10 13, inclusive, are continuations of an electrical network, which, except for my additions, refinements and improvements, is similar to the invention shown and described in the patent to Merwin J. Larsen, No. 2,403,090, July 2, 1946. In carrying 15 my invention into practice, I have so improved and refined certain features of the Larsen invention that the system, as a whole, functions in a greatly superior manner and with attainment of new and highly desirable functional results. Particularly are these refinements and improvements directed to dependable means for 20 suppressing noise heretofore resulting from sudden electron surges when close circuiting the waveform generators of the instrument with the 25 input circuit of an electroacoustical translating system.

In the instant embodiment of my invention, footage stops are an important contribution to the art of electric organs of the class employing 30 generators of waveforms of voltage pulses having the tone frequencies of octavely related musical notes. In instruments having more than a single manual, several factors must necessarily be considered to the end that the range of musical 35 possibilities shall be improved and results attained which are more nearly comparable to the organ than heretofore possible with instruments of the prior art. Such factors include the necessity for securing proportionality in amplitude of 40 divided portions of the output waveform from any single generator when the generator is drawn upon for concurrent use of the same frequency in different parts of the instrument's gamut. As distinguished from the pipe organ and its two or 45 more sets of pipes for as many footage stops, my invention employs a single set of waveform generators from any single generator of which, a waveform of voltage is adapted to be concurrently distributed through different channels according 50 to the number of times the same waveform is used in the rendition of a musical score.

In instruments employing more than one manual and a pedal keyboard, it frequently is necessary to draw upon a single generator for many uses at the same time of the same tone frequency. 55 In fact, the output wave from said generator might possibly be used concurrently a great many times at each manual and at the pedal keyboard in the playing of a musical composition. Instruments employing but a single manual are less complicated, yet, even in this simple instrument, the same frequency might also be used concurrently a great many times if the range of the instrument extends above and below the range of a 60 sixty-one note manual. An example of this would be an instrument employing stops for coupling octavely related frequencies. The herein disclosed invention is that of an instrument of this type. I merely elect this form of disclosure 65 as it entails less complications and neither encumbers this description nor the drawings.

In the pipe organ, proportionality is not a factor for consideration in that footage stops depend entirely upon separate ranks of flues, the flues of 70 each rank functioning separately and apart from

the flues of any other rank, such, for example, 16' flues; 8' flues; 4' flues and 2' flues, to which can be added such mixtures as 16' reeds, 8' reeds and 4' reeds.

As distinguished from a pipe organ, an electric organ must necessarily be reduced to a very minimum of parts. Such instrument must be readily portable and compact and otherwise characterized, that its cost of production is low compared to that of a pipe organ, yet such instrument must have musical possibilities more or less comparable to pipe organs. In the instant embodiment of my invention use is made of a single generator for each note in the instrument's gamut. These generators are substantially the same throughout the entire system. Each generator produces an output signal or waveform of voltage which is rich in harmonics. Any individual generator can be drawn upon for concurrent transmission through the network of the output signal from said generator. The number of times the same waveform is used at any instant will, of course, depend upon the use it is to serve. In order that mathematically correct additive effects can be had, division of voltage from a respective generator must be such that all divided parts thereof that are being concurrently transmitted through the network, shall be of equal amplitude.

The term "frequency" employed herein shall mean—an audio tone signal—regardless of the precise waveform. A more useful waveform for every purpose of my invention, however, is one which is rich in its harmonic composition so as to include a large number of frequencies which are true harmonics of the fundamental.

Referring now to Figures 5 to 13, inclusive, which, when conjoined according to the key chart (Figure 14) form a composite organ network, it is noted that twenty-seven generators C1 to D3, inclusive, are shown as sources of tone signal voltages covering a range of pitches for more than a single octave of notes. A single playing-key is shown at Figure 16 and it will suffice merely to say that each individual generator will be actuatable from a respective playing-key for selective conduction of voltage through the network and resultant activation of a loud speaker. While I have shown a single playing-key, I point to multiple electric switches K1 to K21, inclusive, as indicative of playing-keys 1 to 21 of a short organ keyboard of sixty-one playing-keys. These generators may be of the form shown in Patent No. 2,410,883, November 12, 1946, to Larsen et al., or they may comprise any well known system of generators or alternators for producing complex waveforms of signal voltages at the tone frequencies of different notes of the chromatic scale.

The plate circuit of each waveform generator is provided with an output lead L having parallel high resistive branch paths P1 and P2, such that the waveform of output voltage from said generator can be concurrently transmitted through said network for desired use thereof at the same instant. In each of these branch paths is a series resistance P3 of 1 megohm, the purpose of said parallel resistances being to provide a voltage divider by means of which portions of the output voltage from a generator will be of the same amplitude when said generator is drawn upon for concurrent use of the same frequency. In series with resistance P3 in each branch path P1, P2, is a resistance P4, also of one megohm.

As the ordinary pitch of the organ is 8 ft. play-

ing-key K1 equals 65 cycles per second; playing-key K2 equals 69 cycles per second, etc., to and inclusive of playing-key K61 equals 2093 cycles per second, a tone an octave above playing-key K1 will have a frequency of 131 cycles per second and will be associated with playing-key K13. While my disclosure is confined to means for producing 4-foot and 8-foot tones which may be played separately or together, obviously, this range can be projected either upwards or downwards, limited only by the total number of frequency sources employed and the range of frequencies available from said sources.

It will be apparent to persons trained in the art that limitations upon the extent of octave coupling or ability to obtain given footage tones is confined to the number of generators employed and the range of frequencies produced by said generators. For example, an instrument having but sixty-one generators covering a range of frequencies from 65 cycles per second to 2093 cycles per second will not permit octave coupling beyond a limited range of the keyboard. Increasing the number of generators to provide both higher and lower frequencies obviously increases the coupling range and in those cases where the frequency range has been sufficiently extended, 2', 16', 32', and 64' tones can be produced and the instrument played at any one or all of these pitches. In the instant example, eight foot tones are available from top to bottom of the keyboard. Four foot tones, however, are limited to that section of the keyboard, the playing-keys of which are coactive with generators producing frequencies an octave higher than the ordinary eight foot range of said keyboard.

The following reference chart is indicative of the range of frequencies produced by the twenty-seven generators herein shown and has been extended to include frequencies associated with playing-keys an octave above playing-key K27, thereby providing for the purpose of this disclosure a useful range of both eight and four foot tones.

Referring to Figures 5 to 10, inclusive of the drawings and taking for example, generator $G1=98$ cycles per second, it is noted that connected across branch path $P1$ is a resistance $R20$. Playing-key $K8$ associated with this generator operates adjustable contactors $C10$ and $C11$, the former coacting with resistance $R20$ and the latter with resistance $R21$ connected across path $P2$ from generator $G2=196$ cycles per second, an octave above $G1$. Paths $P2$ from generators $C1$ to $B1$, inclusive, connect to a common ground $G10$. Adjustable contactors $C10$ and $C11$ for each playing-key are connected to ground $G11$. Signal voltage from generator $G1$ is conducted to a collector $B10$ which is common to generators producing output signals, the tone frequencies of which are 92; 98; 104; 110; 117; and 123 cycles per second, constituting one complete key group.

The waveform of voltage from generator $G2=196$ cycles per second is conducted to a collector $B11$ which is common to generators, the tone frequencies of which are 185; 196; 203; 220; 233; and 247 cycles per second and when coupled to generators common to collector $B10$ give four foot tones. This constitutes another key group. Each individual collector of the set of ten collectors herein shown is provided with a common output conductor $L10$ which is connected in the network in a manner to be described presently. These conductors are respectively connected to input leads $G1$ to $G10$ of a wave filter apparatus, detailed reference to which will be made later in this description.

Similarly, all generators embodied in the remaining key groups are connected to respective collectors, each provided with an output conductor $L10$. While I make provision for ten groups only eight thereof are connected in the quality control system as shown at Figures 11, 12 and 13.

Connected across each of said output conductors $L10$ is a variable resistive switch, $R15$. Twenty of such switches are shown, such that there is a gang consisting of ten switches for eight-foot tones and a similar number for four-foot tones. These switches are adapted to be controlled by the customary organ "stop" tabs (not shown). All switches associated with pitches corresponding to an eight foot tone will be connected as a common gang of switches for simultaneous operation from a single "stop" tab. All switches associated with pitches corresponding to four foot tones will be similarly connected for simultaneous operation. It is understood that in any case where the range of footage tones is increased above the number herein shown, each individual playing-key will have its switch number correspondingly increased. According, as these "stops" are drawn, the pitch of the organ is changed. In the instant case if both "stops" are drawn tones in octave relation will speak upon depressing a single playing-key in that section of the keyboard in which provision for coupling is made. Should all stops be in their re-tired positions, the key-switches circuits are broken and no audible sounds can be produced from the keyboard.

Referring to Figures 9 and 10 of the drawings, input leads $G1$ to $G10$ from the respective key groups are each thereof individual to a pre-assigned input division or section of a quality control system to be fully described later in this general description of my invention. At this point, however, and as each input lead of a given key group is a common conductor for signal voltages

75

at frequencies lying in a predetermined band of frequencies, it is necessary to note that these leads are arranged in numerical or successive order of the playing-keys of the organ, such that lead $L1$ from the first or extreme bottom group of playing-keys is individual only to that group. In like manner is this true of each of the remaining groups of keys of which ten such groups constitute the total number of groups employed in this example of my invention, the tenth group comprising seven keys. For an organ embodying a short keyboard consisting of a total of sixty-one playing keys, the frequency of each tone associated with a given playing-key and the grouping of particular playing-keys will be fully understood upon reference to the following chart:

When simultaneously depressing two or more playing-keys, each of which is connected to a generator for concurrent use of divided portions of the same output frequency, leads $L10$ through which these portions are transmitted will connect to a preassigned one of the input leads $G1$ to $G10$. In each of said leads $L10$ is a resistance $L11$ of sufficient value to prevent "robbing" during simultaneous conduction of frequencies from respective generators or when portions of the same frequency are being concurrently conducted from a single generator.

The output of each key group is impressed on the grids of tubes T1, T2 . . . T10 respectively. These tubes may be twin triodes as indicated or separate triodes or pentodes. The function of these tubes is to divide and isolate the groups from each other and also to provide separate isolated output channels for a purpose presently to appear. For example, the grids of T1 are in common, and the cathodes are in common, whereas one plate of one triode is connected to a low-pass filter circuit to activate the filter LP1. The plate of the other triode passes through decoupling resistance 35 to a common lead 117 and also through resistance 37 which, in connection with capacitance 14, suppresses the higher harmonics of the waveforms in the group concerned to a lower level. The output across capacitance 14 passes through decoupling resistance 36 to a common lead 116. Thus, it follows that output from T1 may pass through a plurality of separate output paths. Similar provision is made for the other tubes T2, T3 . . . T10. The filtering capacitances 14, 15, 16 . . . 23, however, differ in value in order to provide essentially the same reactance at the mid-frequency of their corresponding key groups. The magnitudes of these reactances, for example, are substantially the same as the magnitudes of the resistances 37. In the combined Figures 11, 12 and 13, wherein ten high vacuum tube isolators T1, T2, etc., are shown for as many individual groups G1, G2, etc. of playing-key switches, the common cathodes of the odd numbered twin triode tubes are connected to ground by resistive capacitive circuits, including resistance 12 in series between ground and said common cathodes and capacitances 13 in shunt between said resistances and ground, the even numbered tubes being coupled to said resistances at the terminals thereof which connect with said cathodes.

The output from common lead 116 is amplified by a conventional resistance-coupled stage T12, the output of which is fed to conductive lead X2 of the mixing network M. The output of common lead 117, carries a waveform rich in harmonics from resistance 35 in the second output branch from the plate of the right-hand triode of stage T1, and leads to a conventional amplifier stage T13, the output of which is divided, part going to the mixer through lead X3 and the other part going to an amplifier stage T14, which supplies a group of band-pass filters and thence to mixing network M.

These band-pass filters are designated BP1, BP2 . . . BP5 and, as shown, they are coupled to common input lead 119 through decoupling resistances 73, 74 . . . 77. Each of said filters has a separate output lead to the mixer, which leads are designated X4, X5 . . . X8. The characteristics of these band-pass filters will be discussed hereinafter.

The outputs of all of the aforementioned low-pass filters pass to a common lead 118 through

respective decoupling resistances 39, 40 . . . 48, inclusive. The common lead 118 carries the substantially sinusoidal waves of frequencies corresponding to the fundamental components of the respective notes in the instrument's gamut.

5 The output of lead 118 is amplified through the conventional amplifier stage T11, the output of which passes to the mixing network via a lead X1.

10 The function of the mixing network is to provide a means of selecting any number of outputs from the various leads X1, X2 . . . X8 at predetermined amplitudes. This is accomplished by means of decoupling resistances 93, 94 . . . 112 which connect either singly or in groups to simple "stop" switches designated S1, S2 . . . S11. When the switches are "on," the main amplifier 120 activates the speaker 121. When any timbre controlling stop switch is in the "off" position, the contact lever connected to its associated resistance group 93 . . . 112 is grounded through common lead 113 in order to prevent "cross talk."

15 The amplifier input resistance 114 is necessarily much lower than any of the decoupling resistances 93, 94 . . . 112, in order to prevent "robbing" amongst the stops. Likewise the decoupling resistances just mentioned should be higher than the output impedances associated with said common leads X1, X2 . . . X8, although the relative proportioning in this case will depend upon the particular choice of qualities set up for the whole system.

20 Low-pass filter LP1 is designed to start attenuating at F₂ which has a frequency of 87.3 cycles per second. By this means there is no component having a frequency between 87.3 cycles and 130.8 cycles which ever enters the filter, thus providing a wide margin allowing for attenuation. The lowest frequency mentioned outside of the fundamental note range associated with this group, namely 130.8 cycles, corresponds to the frequency of the second harmonic produced by the lowest note C₂ in this particular group. If, for example, the key groups should 25 comprise 12 notes each, the second harmonic of the highest note in that group would be attenuated adequately with a simple low-pass filter, but the second harmonic of the lowest note in that particular group would be attenuated but slightly as it is so close to the frequency of the fundamental of the highest note in said group. It therefore follows that with 12 or more notes in a group a change in tone quality takes place from one end to the other within said group. 30 By means of the aforementioned lesser number, say 6 notes to a group, the difficulties aforementioned are not encountered and a simple low-pass filter can be employed that will function in a highly satisfactory manner.

35 It is, of course, understood that the modus-operandi of all others of the low-pass filters herein employed is substantially the same as that of filter LP1 just above explained.

The purpose of the band-pass filters is to provide a series of formant regions of a number and spacing along the frequency spectrum adequate to provide a choice of tone qualities when used by themselves and/or with other sources associated with the mixing network. The particular band-pass filters employed herein have a rather high coefficient of coupling of between four tenths and five tenths which permits a relatively wide band of frequencies to pass through.

40 The coils 83, 84, 85, 86 and 87 are air-core, wound 45 coaxially, each coil having an inductance of app-

11

proximately 300 millihenries. The capacitances 88, 90, 91 and 92 are adjusted experimentally to provide the desired band-pass region. For example, the mid-frequencies of the bands employed are 500 cycles for band-pass filter BP-1; 800 cycles for band-pass filter BP-3; 1500 cycles for band-pass filter BP-4 and 2200 cycles for band-pass filter BP-5.

Each of these would reinforce predominantly over a range extending approximately half an octave, although the attenuation outside the band is not sharp. One of the filters herein called a band-pass filter, namely, filter BP-2 is simply a loaded resonant circuit having a more narrow pass region which resonates at approximately 1400 cycles. The terminating resistances 73, 79 . . . 82 determine to a large extent the sharpness or Q of the filter. These outputs pass to the aforementioned leads X4, X5 . . . X8 which supply the mixing network.

The waveform of any single note which appears on the output of the common lead 116 is essentially the same in its harmonic constitution irrespective of the note played. Because of the aforementioned selective filtering action of the resistances 37 and capacitances 14, 15 . . . 23, this waveform is predominantly the fundamental together with a large series of rapidly tapering higher partials. This waveform appears amplified on lead X2 which supplies the mixing network. It should be noted here that successive filtering by resistance-capacitance networks would require a very large array of sections before a more flute-like tone quality would be possible which would compare with the low-pass filters. This follows because, in capacitance-resistance networks higher partials are suppressed, yet are not completely obliterated as with the low-pass filters just described. The waveform of any tone on the common lead 117, on the other hand, is richer in harmonic output as the only integrating action employed is that of capacitances 1, 2, . . . 10 which are associated with their respective key groups G1, G2 . . . G13. If the individual tone generator output waveform is rich in harmonics as the case in the generator disclosed in said Patent No. 2,410,883, then the waveform appearing on lead 117 is still moderately rich in its harmonic composition. This waveform appears amplified on lead X3 which connects to the mixing network and is also the same waveform which appears further amplified on the common lead 119 which supplies the aforementioned band-pass filters.

No claim is made to the features herein set forth and pertaining to the patent to Merwin J. Larsen, No. 2,403,090, it being merely intended that it shall serve to meet all statutory requirements for a full and complete disclosure of a practical embodiment of my invention. Regarding reference herein to multivibrators or relaxation oscillators as tone frequency sources, it shall also be understood that these equally serve my purpose and likewise are a statutory reference to one known means for practicing my invention. Any other well known type of waveform generator might possibly be substituted therefor with equally satisfactory results.

No claim is made to the aforementioned quality control and mixer systems shown and described herein apart from use therein in the described combination with those new and novel features which form my contributions and improvements, namely, those changes and embodiments including the various circuit constants such as (1) par-

12

allel resistive conductive paths common to pre-assigned tone frequency generators and functioning to enable conduction of respective portions of signal voltage along different paths for use simultaneously according to selective use of given stops, and whereby, and incident to their use in the environment herein shown, said respective portions of said signal voltage are of equal amplitude; (2) resistive switches in shunt with the respective conductive paths for suppressing noise otherwise occurring and resulting from sudden electron surges when closing the keying switches.

In a system of tone generation wherein waveforms of signal voltages are changed by a system of filtering, to provide waveforms following the wave patterns of various timbres, the highest measure of efficiency of such systems can be attained only in those cases where extraneous frequencies are eliminated and excluded from the input of the amplifier as otherwise the wave patterns sought to be produced by the process of filtering will not be as predetermined. The resultant tones will be unclean or marred. My resistive switches functioning as herein set forth are therefore electrically coactive with said filter system to the end that new and highly beneficial results are assured and tones produced which are much closer approximations to tones of given timbres. Noise which heretofore has blurred resultant tones is also effectively suppressed. The percussiveness characteristic to electric organs is eliminated by progressively increasing and decreasing the keyed resistance, and while this does not function precisely according to the characteristic attack and decay of tones produced by a pipe organ and therefore is not a means for controlling the attack and decay of tones, said keyed resistances are highly dependable and, in addition thereto, are inexpensive by reason of elimination of costly time controlled devices in which the attack and decay of tones is a function of time, namely, the time to charge and discharge a condenser. My invention functions merely to determine the amplitude of the wave being conducted through the network of the system according to the depth of depression of a playing-key on the velocity of the key. Should the key be depressed to a fixed depth between two possible extremes, and this position maintained, the amplitude will remain constant. The player, however, has control of this situation as the amplitude can be increased by further depression of the key or it can be diminished by removing pressure therefrom. These are found to be advantages, however, rather than disadvantages.

A multiple switch mechanically designed to function as aforesaid comprises a strip 50 of Bakelite or other well known electrically insulating material formed on one side with sensibly identical grooves 51, 51, each terminating at its front end in a fixed contact element 52 adapted to be connected across a tone frequency transmission channel of the electrical network herein shown and described. Each of these grooves is provided with a carbonaceous coating substance so applied that the resistance is of a variable value such that it increases in a direction away from said fixed contact. Connected to ground and coactive with each groove is a rectilinear springy contactor 53 which is urged to a position in parallelism with the groove so as uniformly to engage the carbonaceous coating in said groove. A spring 54 coacts with said springy contactor to hold same uniformly against said coating and in

33
13 yielding engagement with said fixed contact element. Each springy contactor has a foot piece 55 and, as shown at Figure 16, same is in coactive relation to the back end of playing-key 56; whereby upon depressing said key, said springy contactor will gradually peel off of said carbonaceous coating, thereby progressively varying the resistance from a zero value to whatever may be a predetermined maximum value of said resistance.

A multiple switch designed as herein shown and described is so characterized that it may be made of minimum width, to adapt itself to playing-keys of customary width at their back ends. Such switches can also be made in gangs or assemblies, each gang or assembly designed for an octave of playing-keys.

The three element oscillators shown herein as generators are employed mainly for the purpose of simplicity, yet this type of oscillator can be used with equal success as my invention is not dependent upon a specific type of oscillator. An oscillator of the three element type is disclosed in U. S. Letters Patent No. 1,791,319, of February 3, 1931, to F. E. Miller, and would serve my purpose when used in the manner herein stated.

Resistances P3 and P4 are each thereof one megohm. Resistances R15 and L11 are each thereof one-half megohm. Blocking condensers C in the output paths L from the respective generators may be of any value calculated to prevent passage of direct current to the wave filtering apparatus, and to maintain approximate constant reactance to the signal voltage.

What I claim as my invention is:

1. A musical instrument comprising a keyboard; an electrical network having an electro-acoustical translating system; a plurality of generators producing signal voltages at tone frequencies for a range of more than one octave of notes of a musical scale, said network having a plurality of transmission channels for and common to each individual playing-key of said keyboard and to assigned octavely related generators of said plurality of generators; and means for effecting selective activation of said translating system in response to tone signal voltage from one or more octavely related generators common to playing-keys depressed at any instant, said means including an electric switch in each channel of said plurality of channels common to a respective playing-key, and respective, selectively actuatable gangs of electric switches connected in said network and with said transmission channels so that, and in response to close circuiting of the switches of any gang of switches, signal voltages from selected generators will be transmitted through selected ones of the aforementioned channels for activation as aforesaid of said translating system.

2. In an octave coupler for electronic organs employing a work circuit, a plurality of sources respectively producing complex tone signals at the frequencies of notes of the chromatic scale, and a keyboard providing a playing-key for each note in said scale; said coupler comprising mechanism actuatable as desired for conducting to said work circuit signal voltage which is the sum of separate signal voltages in octave relation produced by preassigned ones of said sources and including, in combination, a plurality of output paths from each separate source of said plurality of sources, each of said paths having resistances in series, variable resistances common to and controlled by preassigned playing-keys and respectively connected to output paths of octavely

14 related sources, each variable resistance having a terminal connected to a respective one of said paths at the juncture point between the series resistances therein, and selectively actuatable devices enabling conduction of said signals to said work circuit upon actuation of selected playing keys, the aforementioned sources arranged in groups, such that the sources of each separate group respectively provide a predetermined band of frequencies, each of said groups of sources having an output conductor common only to the sources of that group.

3. An octave coupler as set forth in claim 2 wherein a tone filter system is connected with the output conductors of said groups.

4. An octave coupler as set forth in claim 2 wherein a tone filter system is connected with the output conductors of said groups and a mixer is connected to the filter system for combining the outputs of different filters of said filter system.

5. In a coupler for electronic organs employing a work circuit, a plurality of sources respectively producing complex tone signal voltages at frequencies embracing more than an octave of notes of the chromatic scale, and a keyboard providing a playing-key for each note, said coupler comprising mechanism actuatable as desired for conducting to said work circuit signal voltage which is the sum of separate voltages produced by preassigned ones of said sources, in combination with a plurality of output paths from each separate source, and selectively actuatable devices enabling the aforementioned conduction of said signal voltages to said work circuit upon actuation of selected playing-keys, the aforementioned sources arranged in groups such that the sources of each separate group respectively produce a predetermined band of frequencies, each of said groups of sources having an output conductor common only to the sources comprising that group.

6. A coupler as set forth in claim 5 wherein a tone filter system is connected with the output conductors of the respective groups of said sources.

7. A coupler as set forth in claim 2, wherein a tone filter system is connected to the output conductors of the respective groups of said sources and a tone filter system is connected in common to all of said conductors.

8. A musical instrument comprising a keyboard; an electrical network having an electro-acoustical translating system; a plurality of generators respectively producing signal voltages at tone frequencies for a range of more than one octave of notes of a musical scale, said generators arranged in groups such that the outputs of each separate group thereof are at tone frequencies corresponding to the vibration frequencies of given sequentially related notes of said musical scale; and comprise frequencies lying in a given band of frequencies; a system of stops interposed in said network between said translating system and said generators and in which assigned ones of said stops are connected to generators whose outputs have a given frequency relation to each other; a plurality of keying circuits for and common to each separate playing-key of said keyboard and actuatable by said key to effect transmission of the outputs of given generators to said translating system upon drawing one or more of said stops; means electrically coactive with said system of stops for isolating from each other frequencies lying in the different bands of frequencies, and a wave filter system interposed between said isolating means and said translating system.

15

9. In an electronic keyboard musical instrument, a translating device, sources producing complex audio signals at tone frequencies for more than an octave of notes of the chromatic scale; a plurality of collectors, each separate collector connected to predetermined ones of said sources such that each separate collector is individual only to sources producing complex audio tone signals at the tone frequencies of notes associated with a given number of sequentially related playing-keys of said keyboard, each of said collectors having an output conductor, connected with said collectors, and mechanism including keying circuits, actuatable by said playing-keys and connected to said sources for conduction of the outputs therefrom, wave filtering means for repeating the outputs from said sources as outputs having predetermined harmonics above the fundamental frequencies of the first named outputs, a system of stops for selectively coupling the out-

15

puts of sources associated with given playing-keys with the outputs of sources associated with others of said playing-keys and for effecting transmission of the coupled outputs to said translating device.
